UNITED STATES PATENT OFFICE.

HUGO F. RIPKEN, OF MINNEAPOLIS, MINNESOTA, ASSIGNOR OF ONE-HALF TO
CHARLES A. McCULLOCH, OF MINNEAPOLIS, MINNESOTA.

DRIFTING AND RELIEF VALVE.

Application filed August 24, 1921. Serial No. 495,027.

To all whom it may concern:

Be it known that I, HUGO F. RIPKEN, a citizen of the United States, residing at Minneapolis, in the county of Hennepin and 5 State of Minnesota, have invented certain new and useful Improvements in Drifting and Relief Valves, of which the following is a specification.

My invention relates to improvements in 10 drifting and relief valves for reciprocating steam engines, and especially for those employed in railway locomotives using superheated steam. The present invention is an improvement intended for use in the construction 15 of valves of the type shown in the United States Patent, No. 1,280,848, issued to me October 8, 1918, and has for its object, to provide means whereby the piston will be positively held to its seat, in its normal inactive 20 position. It will be noted, that in the valve described in the above named patent, piston ring friction, and the weight of the piston itself is wholly relied upon to hold it to its seat. To prevent accidental movement of 25 same, due to inaccurate workmanship, and add to its stability, in its normal seated position, to secure at all times positive, uniform action, I employ novel and effective means, whereby the descending piston, by its 30 movement from operative to inoperative position, develops an annular chamber, which opens to communication with a constant live steam area, as the piston approaches its seat, the piston being provided with a relatively 35 small pressure receiving surface or shoulder within the developed chamber, the pressure on said shoulder serving to hold it on its seat.

More particularly, the invention consists 40 in the construction, combination and arrangement of parts hereinafter described and claimed.

In the drawings:

Figure 1 is a vertical longitudinal section- 45 al view through the center of the cylinder and steam chest of a reciprocating engine with my improved valve shown in full.

Figure 2 represents a vertical sectional view through the center of the valve body, 50 showing the valve proper in its normal position and Figure 3 is a similar view showing the valve in operating position.

The general operation of the valve shown, is substantially similar to that of the valve

forming the subject of the patent men- 55 tioned in the foregoing, with the exception of the auxiliary steam pressure on the piston in its downward movement.

In the drawings A represents the cylinder of a reciprocating engine, B the piston working thereon, and C the steam chest in which works the valve piston D, all of usual type.

My improved valve comprises a cylindrical casing or valve body 2, the interior of which is open to communication with one end of 60 the interior of the cylinder through the medium of the threaded nipple 3 at the lower extremity of the valve body, the interior of the nipple leading into a duct 4 which latter extends around a bushing at one end 65 of the steam chest to the cylinder port 5 on that side of the piston B.

The compressed air or steam in that end 70 of the cylinder will thus pass through the duct 4, into the lower part of the valve casing, under the valve, hereinafter described.

Leading from the top of the casing 2 to the main steam supply pipe or conduit E, and communicating with the interior thereof is an auxiliary steam supply pipe 6 com- 75 municating with the interior in the top of the casing 2, the casing being provided with a live steam inlet 7 at one side thereof, projecting laterally therefrom, which inlet 80 is open to communication with the pipe 7^a 85 which is connected with a source of live steam supply such as the dome of the boiler.

Working within the valve casing 2 is a sliding hollow valve piston 8, having an inset bottom, forming an inverted cuplike 90 lower portion. The upper portion of the piston is of enlarged diameter, forming at the point where it joins the lower portion, a circular flat seat or shoulder 9, which seats on a co-operating shoulder 9^a in the 95 casing.

The piston may therefore be termed a differential piston as it has a top and bottom of different diameters and main and auxiliary bottom surface. A row of spaced 100 oblong ports 10 surround the piston and pierce the peripheral wall of the upper portion thereof, suitable piston rings 18 and 10^a being provided respectively above and below the ports and located immediately adjacent thereto to prevent leakage.

A bushing 11 adapted to slidably receive the piston 8, forms an inner cylindrical wall

for an annular groove cast in the wall of the casing, thereby forming the annular walled-in chamber portion 11' of the inlet 7, the latter being open to communication 5 with the interior of the supply pipe 7^a. This inner wall of the inlet chamber is pierced by a circumferential row of ports 13, which are arranged to register with the ports 10 when the piston 8 is slid upward against 10 the shoulder 14 in the casing.

Leading downwardly from the annular chamber portion, of the inlet 7, and from the casing wall, and opening into the interior of the casing at a point above the 15 shoulder 9^a (whereon the piston normally rests) by means of the port 15 is a duct 15^a, the port being guarded against leakage by the rings 10' and 10'' carried by the piston. The lower portion of the piston is 20 of reduced diameter as at 8' owing to the shoulder 9, and is provided with the packing ring 9' to prevent steam from the steam chest from passing between the piston and the casing at this point.

25 Opposite the port 15, piercing the wall of the casing at a point in the shoulder 9^a is a vent 16 which acts as an exhaust and may open to the atmosphere, or be connected with the exhaust chamber as shown 30 in Figure 1.

In operation, when the throttle valve, not shown is closed, the pressure in the conduit immediately thereafter falls or is reduced, while the piston B (Fig. 1) will travel, 35 (while the engine is drifting), to the right, compressing the gases before it, and producing a back pressure in the cylinder, in the port 5, and in the duct 4. This back pressure is communicated to the bottom of the valve piston 8, causing it to be lifted 40 from its seat 9^a in the casing and slid upwardly until it abuts against the shoulder 14. When in this position, as hereinbefore stated, the ports 10 and 13 are in register, 45 thereby establishing communication between the interior of the pipe 7^a and the interior of the casing.

50 Live steam from pipe 7^a will now pass (as indicated by the arrows Fig. 1) through the inlet into the casing 2 above the valve piston and through the medium of pipe 6 and conduit E enter the steam chest and cylinder, where it will prevent any vacuum forming tendency behind the piston because 55 the pressure in the conduit (when the throttle is closed) is counter-acted only by the back pressure generated by the piston and the friction of the packing rings (on the valve piston) and which cannot be relied upon to maintain the valve piston in operating position and prevent a fluctuating movement thereof. The port 15 and the shoulders 9 and 9^a, respectively, of the valve piston 8 and the casing are provided to permit steam to enter the port 15, and thence

enter the cavity formed between said shoulders when the piston is moved upward to hold the piston 8 in operating position.

As the valve piston 8 is automatically raised, (by pressure generated in the cylinder), it uncovers the port 15 to admit live steam to the annular cavity formed between the seat 9 and its cooperating shoulder 9^a in the casing (when the valve piston is moved) the steam pressure in the cavity serving to 75 regulate the pressure which causes the downward movement of the piston as will be hereinafter explained.

The vent 16 admits air to the cavity to prevent creation of a partial vacuum therein (when the valve piston is raised) which would otherwise tend to oppose the back pressure generated in the cylinder. It also acts as a restricted outlet for the inrushing steam, the vent 16 being appreciably smaller than the inlet port 15, resulting in back pressure in the cavity, whereby the piston is controlled to descend only when there is excessive steam pressure above it, which occurs when the engine is drifting very slowly 90 or actually comes to rest.

When the engine comes to rest the valve piston descends, covering the ports 10 to cut off the live steam supply and then covering the port 15 from which point it will slowly 95 descend, riding on the air or steam pocketed in the cavity which is now expelled through the restricted vent 16 by the descending piston, whereafter the piston valve comes to rest on its seat.

100 The foregoing descriptive matter relating to construction and operation is found in my prior patent hereinbefore mentioned, and the subject of my present invention may now be described as follows.

105 In my prior patent, the weight of the piston and piston ring friction, are relied upon to hold the valve 8 to its seat 9. In the present construction the sleeve 11 extends a relatively small distance beyond the annular chamber portion of the inlet 7, and is formed with an inwardly and downwardly beveled edge 17.

110 The piston 8 is slightly reduced in diameter beginning at a point just above the piston ring 18 which latter is above and adjacent the ports 10, the reduced portion being of uniform diameter and having a packing ring 18' adjacent its upper edge.

115 The upper portion of the valve body is formed with a detachable section 19 and is securely attached by the cap screws 20, said section being suitably threaded to receive the threaded end of the conduit E. The section 19 carries the shoulder 14, and is 120 formed with an annular flange 20' of uniform inner diameter to slidably receive the reduced portion of the piston and its packing ring 18', when the piston is in its normal seated position. The annular flange is 125 130

beveled to match the angularity of the beveled edge 17 of the sleeve 11 so as to telescope into the latter. As the inner diameter of the sleeve is uniform, a relatively small 5 annular chamber 21 is thereby formed, the latter surrounding the piston and extending, as shown, into open communication with the ports 13, so that the pressure in the live steam inlet 7 will prevail in said chamber. 10 Thus, the pressure on the shoulder 22 formed by the slight variation in the piston diameter, constantly holds the piston to its seat.

In operation, when the locomotive is drifting and the steam supply is cut off, the piston will be actuated (in opposition to the pressure on the shoulder 22) by the back-pressure in the cylinder, as stated in the foregoing, until it assumes the position indicated in Figure 3, in which position, steam is entering the cylinder through the conduit E, and the packing ring 18 is positioned at a point above the ports 13, thereby cutting off the steam supply for the chamber 21, and thereby relieving the piston of the downward pressure on the shoulder 22, thus facilitating the upward movement thereof as it approaches the shoulder 14. A clearance space 23 is provided at the top 20 of the piston, from which space lead the radial ducts 24, whereby pocketing of air or steam is prevented at that point which might otherwise retard the action of the piston. It will be noted that the shoulder 25 of the piston will arrive at the port 15 (in the downward movement of the piston) approximately at the same time that the top of the ring 18 will arrive at the upper edges of the ports 13, thereby enabling the pressure in the chamber 21 to be added to the force of gravity due to weight of the piston in expelling (through the vent 16) air and steam from the cavity between the shoulders 9 and 9'. The normal function 30 of the port 15 and the duct 15^a, in association with the cavity formed responsive to the movement of the piston, remains undisturbed by the action of the steam pressure in chamber 21, except that the piston in its downward movement is slightly accelerated.

I claim:

1. A drifting valve, comprising a valve casing in open communication with a steam supply line, a differential valve member slidably mounted in the casing, said valve having a drifting condition and a normal condition, means to close said supply line when the valve is in a normal condition, a passage in open communication with the casing and with the steam chest of an engine with which the device is to be associated, means to admit steam from the supply line to the steam chest of said engine when the valve is in a drifting condition, a steam by-pass 55 opened by the operation of the valve to con-

duct steam from the steam supply line to an offset portion of the differential valve to sustain the valve in a drifting condition, and a chamber in open communication with said steam supply line when the valve is in a normal condition, said chamber having a bottom formed by an offset portion of the valve and a top formed by part of the casting to exert a downward pressure on the valve when in a normal condition. 70

2. A drifting valve, comprising in combination a piston, slidably mounted in a casing to have a normal and an operated position, said casing having a top, a bottom, and a side opening, the top opening being connected to a steam supply line during a power operation of an engine with which the drifting valve is associated, the bottom opening being connected to the compressive side of said engine when the engine is drifting, and the side opening being connected to a steam supply line and being normally covered by the valve piston, the valve piston being shaped to uncover said side opening when the valve piston is operated to bring said side opening into communication with the steam chest of the engine, and a chamber formed by an offset portion on the casing and on the valve piston to be in open communication with the side opening when the valve piston is in less than a fully operated position. 85

3. A drifting valve comprising a casing open to communication at its lower end with the cylinder of an engine and at its upper end with the steam chest thereof, a ported member slidably mounted in the casing to have a normal and an operated condition, said member being operated by pressure in the engine cylinder on the compression side of its piston when the engine is drifting, a steam inlet in the casing in the path of said ported member to register with the ports thereof when said device is operated, and means on the ported member and on the casing to be sealed from said steam inlet when said ported member is in an operated condition and to be in open communication with said steam inlet to form a downward propelling surface for the ported member when said ported member returns to a normal position. 100

4. A drifting valve comprising a casing open to communication at its lower end with the cylinder of an engine with which the drifting valve is associated and at its upper end with the steam supply line therefor, a ported member slidably mounted in the casing to have a normal and an operated condition, said member being operated by pressure in the engine cylinder on the compression side of its piston when the engine is drifting, a steam inlet in the casing in the path of said ported member to register with the ports thereof when said device is oper- 105 110 115 120 125 130

ated to supply steam to the steam chest of the engine, and means on the ported member and on the casing to form an auxiliary downward propelling surface acted upon by steam from said steam inlet when the ported member is in less than a fully operated condition.

5. A drifting valve comprising a casing in open communication at one end with the cylinder of an engine with which the valve is associated and at the other end with the steam chest of said engine and having a steam inlet intermediately of said casing, a ported slidale member having a shoulder thereon mounted in the casing to have a normal condition and an operated condition, the slidale member normally closing the steam inlet and being operable by pressure in the cylinder when the engine is drifting

to register said ports with said steam inlet, a duct in the casing from said steam inlet to the interior of the casing above said shoulder, said duct being normally closed by the slidale member and being opened by an operation of the slidale member to admit steam through said duct into contact with the slidale member below said shoulder to impart an upward movement thereto, and a chamber formed by an offset portion on the slidale member and an offset portion on the casing, said chamber being in open communication with said live steam inlet during a return of the slidale member to normal.

In testimony whereof I affix my signature.

HUGO F. RIPKEN.
